CARLETON JOSEPH BARTON, OF CHICAGO, ILLINOIS.

PROCESS OF TREATING VEGETABLE OILS.

1,310,977.

Specification of Letters Patent. Patented July 22, 1919.

Application filed September 22, 1917. Serial No. 192,743.

To all whom it may concern:

Be it known that I, CARLETON JOSEPH BARTON, a citizen of the United States of America, and a resident of Chicago, county 5 of Cook, and State of Illinois, have invented certain new and useful Improvements in Processes of Treating Vegetable Oils, of which the following is a specification.

The main objects of this invention are to 10 provide an improved process of refining or separating into constituent parts, vegetable oils and particularly oil obtained from maize or corn; to provide a refining process of this kind in which neither acids nor alkalis are used; to provide a process of separating corn oil into the three parts: (A) the non-emulsified oil, (B) the emulsified oil, and (C) that constituent part of the 15 original oil which, as a result of the emulsifying, appears as wax; to provide a process by which the three portions which are chemically and physically different may be each returned to the appearance of the original oil; to provide a process of separating out 20 an edible stable oil without any unnatural acid or alkali taste; to provide a process which returns the emulsifiable oil to original appearance; and to provide a process which returns the wax portion to original appearance. 25

An illustrative embodiment of this invention is shown in the accompanying drawing, in which:

Figure 1 is a diagrammatic outline of the 30 complete process.

Fig. 2 is a diagrammatic view of the centrifuge used for one of the steps of the improved process.

Heretofore in the treating of maize or 35 corn oil, the crude oil was heated to approximately 115 degrees Fahrenheit, and caustic soda was added to neutralize the so termed free fatty acids and precipitate the foots. Two products were obtained by this process, 40 the most important being the neutral oil used for culinary purposes; the other product was the foots, and contained neutral oil, glycerin and soap. The non-emulsified product was then filtered through 45 fullers' earth, and then cleaned by live steam. This filtered product, while edible, possesses an objection, in that the product has a slight flavor which would not be present if no alkali was used in the process.

50 The foots, being the precipitated portion containing glycerin, soap and neutral oil,

is usually utilized in the soap making industry as a basis for cheap soaps.

With the improved process herein set forth, a much larger proportion of non-emulsified edible oil is obtained, and it is free from any objectionable flavor.

The process comprises the agitation of crude maize oil with water or live steam, heating to a temperature sufficiently high to 65 cause a partial separation of the non-emulsified oil from the emulsified portion and the water. The best temperature for this purpose has been found to be approximately 70° centigrade. By this step of the process, 70 non-emulsified oil to the extent of approximately 65.7 per cent. of the original volume may be separated, preferably allowing the oil to stand for approximately twenty hours, but this separation may be accomplished by mechanical means in less time. 75

The remaining part of the original mixture, or approximately 34.3 per cent. of the original volume, still contains considerable non-emulsified oil. In order to extract this 80 non-emulsified oil the emulsion is reheated with water or steam to a temperature sufficiently high to permit the separation by mechanical means of the non-emulsified oil from the emulsified oil and water. In practice 85 approximately 100 degrees centigrade has been found to produce the best results.

When this emulsion has been reheated, it is then, while still hot, run through a specially constructed centrifuge, such as shown 90 in diagrammatic outline in Fig. 2 of the drawings. The centrifuge comprises a receiving bowl 1, a feed pipe 2, a separating bowl 3 of the usual design. It has been found, however, in practice that when it 95 was attempted to pass the hot emulsion through a centrifuge, the machine became clogged with the thick emulsion and would not operate, and it has therefore been impossible heretofore to secure any additional 100 separation of the oils. This difficulty has been overcome by placing a pipe 4 in the receiving bowl 1, so that the lower end thereof leads into the feed pipe 2 at the bottom of the bowl. Boiling hot water is passed 105 through this pipe 4 immediately preceding the passing of the emulsion from the bowl 1 into the feed pipe 2, and the addition of this hot water is continued during the entire centrifuging process, the quantity of 110 water supplied being of substantially equal volume to the amount of emulsion.

The boiling water that passes into the separating bowl 3 is thrown immediately outward to the sides thereof and forms a layer between the separating bowl and the emulsion. This separating layer of hot water prevents any clogging of the separating bowl and as a result an additional non-emulsified oil to the extent of approximately 5 to 10 per cent. of the original volume is 10 separated and drawn off from the emulsion.

The balance of the emulsion is then placed in a suitable receptacle and boiled with a dehydrating or any other agent that will break down the emulsion, such as common 15 salt. This emulsion with the breaking agent therein is then boiled for some time until nearly all of the separated water is boiled off, and allowed to stand, whereupon it separates into three layers, the top layer being 20 the converted emulsion (an oil), the center layer being a layer of the unbroken or unconverted emulsion, and the lower layer being the solution of the water and breaking agent. The clear top layer may then be 25 decanted and this decanted oil is clear like the original product, maize oil, but of a slightly darker color and a butter-like taste. This oil which has a butter-like taste I have named B-oil. The corn wax is a valuable 30 product of which use is made in the industrial arts.

The corn wax is not soluble in alcohol, but when boiled with the alcohol is dehydrated and floats on it. After separating, 35 the last trace of alcohol is removed from the C-oil by heating to 130° centigrade. It then has an appearance like the original corn oil.

An alternate process accomplishing the 40 same result is that of slowly and gently heating the wax-like emulsion after it has been spread into a thin surface, as in a film or drum evaporator. Proper temperatures are maintained to insure success.

45 The complete process comprises the separation of maize oil into three separate and distinct oils as regards chemical compounds and physical characteristics.

Each of the oils has its use in the arts:

50 Oil A: The non-emulsified portion.

Oil B: The converted emulsified portion from which the wax-like portion has been removed.

Oil C: The wax-like portion converted 55 into its original physical condition.

The invention may be more specifically illustrated by the following example: Place ten pounds of corn oil in a fluid tight receptacle and add five pounds of boiling hot 60 water. Then maintain the temperature at about the boiling point for twenty-five minutes by introducing a vigorous supply of live steam which serves also to agitate the material. A lower temperature and other 65 stirring means may be employed. As a re-

sult of this treatment about 34.3 per cent. of the oil becomes emulsified whereby about 3.43 pounds of emulsion is produced. Separation may be effected by gravity or more quickly by a centrifuge. This emulsion is 70 then treated by mixing with about an equal weight of boiling hot water. The material is then run through a special centrifuge, such as shown in Fig. 2, whereby a second emulsion and a non-emulsified oil are obtained, the latter being about 15 per cent. of the original volume of corn oil or about one and one-half pounds.

The next step is to take a quantity of the second emulsion, say three pounds, and add 80 5 per cent. of salt, *i. e.*, about .15 pound, and say three pounds of hot water. This is kept boiling hot or nearly so for about twenty minutes whereupon it is permitted to cool. As said material cools, it separates 85 by gravity into three layers. The upper layer consists of clear "B" oil somewhat darker than the original corn oil. The middle layer consists of corn wax, and the lower layer consists of salt brine. The proportions respectively are about:—2 pounds of "B" oil, 1 pound of wax and the remainder being brine and impurities.

A quantity of corn wax, say 1 pound, is then dissolved in about an equal weight of 95 alcohol. The free alcohol is then distilled off leaving about 1 pound of clear "C" oil.

Although certain definite temperatures, percentages, and time intervals have been stated herein, it is to be understood that 100 these may be deviated from and satisfactory results still obtained, and that details of the process may be altered or omitted without departing from the spirit of this invention as defined in the following claims.

105 I claim:

1. The process of treating corn oil, which comprises the heating of said oil with steam or water to a temperature sufficiently high to produce an emulsion, removing by means of decantation such part of the non-emulsified oil from the warm emulsified oil and water as may be separated by a brief interval of standing, reheating with additional water the emulsion so obtained to a 110 temperature sufficiently high to permit the balance of the non-emulsified oil to be separated, while hot, with a centrifuge, and passing such emulsion through a centrifuge and thereby effecting such separation.

2. The process of treating corn oil, which comprises the heating of said oil with steam or water to a temperature sufficiently high to produce an emulsion, removing by means of decantation such part of the non-emulsified oil from the warm emulsified oil and water as may be separated by a brief interval of standing, reheating with water the emulsion so obtained to a temperature sufficiently high to permit the balance of the 115 120 125 130

non-emulsified oil to be separated, while hot, with a centrifuge, and passing such emulsion, while hot, through a centrifuge with a substantially equal volume of hot water, and so effecting such separation.

3. The processes of treating maize or corn oil, which comprise the agitation of said oil with steam or water at a temperature sufficiently high to produce an emulsion and to cause part of the warm non-emulsified oil to separate by gravity, upon standing, from the emulsified oil and water, the removal of such part by decantation, reheating with the water the emulsion so obtained to a temperature sufficiently high to permit the balance of the non-emulsified oil to be separated, while hot, with a centrifuge, passing such emulsion through a centrifuge and thereby causing such separation, the addition of a breaking agent to the emulsion last obtained, and the heating of said emulsion to a temperature sufficiently high to cause a breaking of part of the emulsion into an oil and the separation by gravity of this from the unconverted waxlike portion of the emulsion and the water containing the breaking agent.

4. The processes of treating maize or corn oil, which comprise the heating of said oil with steam or water followed by standing to a temperature sufficiently high to produce an emulsion and thereby causing part of the warm non-emulsified oil to separate by gravity, upon standing, from the emulsified oil and water, reheating with the water the emulsion so obtained to a temperature sufficiently high to permit the balance of the non-emulsified oil to be separated, while hot, with a centrifuge, passing such emulsion with a substantially equal volume of hot water through a centrifuge to cause such separation, the addition of a breaking agent to the emulsion last obtained, and the heating of said emulsion and thereby causing a separation of the converted emulsion, the waxlike unconverted emulsion and the water solution of the breaking agent.

5. The process of treating maize or corn oil, which comprises the agitation of said oil, with steam or water, and thereby producing an emulsion, heating to a temperature sufficiently high to cause part of the non-emulsified oil to separate by gravity, upon standing, from the emulsified oil and water, reheating with water the emulsion so obtained, to a temperature sufficiently high to permit the balance of the non-emulsified oil to be separated, while hot, with a centrifuge, passing such emulsion through a centrifuge and thereby causing such separation, adding a breaking agent that will break down the colloidal state of the emulsion last obtained, heating said emulsion to a temperature sufficiently high to cause a separation of the converted emulsion and the un-

converted portion and the water solution of the breaking agent, and subsequently cooling the converted emulsion and thereby causing a further precipitation of the unconverted part of the emulsion.

6. The process of treating maize or corn oil, which comprises the agitation of said oil with steam or water to form an emulsion, heating of said emulsion to a temperature of substantially 70 degrees centigrade so as to cause part of the non-emulsified oil to separate by gravity, upon standing, from the emulsified oil and water, separating the non-emulsified oil from the emulsified oil and water, reheating with water the emulsion so obtained, to a temperature sufficiently high to permit the balance of the non-emulsified oil to be separated, while hot, with a centrifuge, passing such emulsion through a centrifuge to cause such separation, adding a breaking agent that will break down the colloidal state of the emulsion last obtained, heating said emulsion to a temperature sufficiently high to cause a separation of the converted emulsion, the unconverted emulsion, and the water solution of the breaking agent, and subsequently cooling said converted emulsion to cause a further precipitation of the unconverted part of the emulsion.

7. The process of treating maize or corn oil, which comprises the agitation of said oil, with steam or water, to form an emulsion, the heating of said emulsion to a temperature sufficiently high to cause part of the non-emulsified oil to separate by gravity, upon standing, from the emulsified oil and water, separating the non-emulsified oil from the emulsified oil and water, reheating with water the emulsion so obtained, to a temperature of substantially 100 degrees centigrade so as to permit the balance of the non-emulsified oil to be separated while hot, with a centrifuge, passing such emulsion through a centrifuge to cause such separation, adding a breaking agent that will break down the colloidal state of the emulsion last obtained, heating said emulsion to a temperature sufficiently high to cause a separation of the converted portion, the unconverted portion, and a water solution of the breaking agent, and subsequently cooling said converted portion to cause a further precipitation of the unconverted portion.

8. The process of treating maize or corn oil, which comprises the agitation of said oil, with steam or water, to a temperature sufficiently high to produce an emulsion and to cause part of the non-emulsified oil to separate by gravity, upon cooling, from the emulsified oil and water, separating the non-emulsified oil from the emulsified oil and water, reheating with water the emulsion so obtained to a temperature sufficiently high to permit the balance of the non-emulsified oil to be separated, while hot, with a cen-

- trifuge, passing such emulsion through a centrifuge to cause such separation, adding NaCl to the emulsion last obtained, heating said emulsion to a temperature sufficiently high 5 to cause a separation of wax, and subsequently chilling said emulsion to cause a precipitation of the wax.
9. The process of treating maize or corn oil, which comprises the heating of said oil, 10 with steam or water, to a temperature sufficiently high to produce an emulsion and to cause part of the non-emulsified oil to separate by gravity, upon cooling, from the emulsified oil and water, separating the non- 15 emulsified oil from the emulsified oil and water, reheating with water the emulsion so obtained, to a temperature sufficiently high to permit the balance of the non-emulsified oil to be separated, while hot, with a centrifuge, passing such emulsion through a centrifuge to cause such separation, adding an 20 electrolyte that will break down the colloidal state of the emulsion last obtained, heating said emulsion to a temperature of substantially 25 100 degrees centigrade, so as to cause a separation of wax, and subsequently chilling said emulsion to cause a precipitation of the wax.
10. The process of treating maize or corn oil, which comprises the heating of said oil with steam or water, to a temperature sufficiently high to produce an emulsion and to cause part of the non-emulsified oil to separate by gravity, upon cooling, from the emulsified oil and water, separating the non-emulsified oil from the emulsified oil and water, reheating with water the emulsion so obtained, to a temperature sufficiently high to permit the balance of the non-emulsified oil 30 35 40 45 50 55 60 65 70 75 80 85 90 95 to be separated, while hot, with a centrifuge, passing such emulsion through a centrifuge with water to cause such separation, adding an electrolyte that will break down the colloidal state of the emulsion last obtained, heating said emulsion to a temperature sufficiently high to cause a separation of wax, and subsequently chilling said emulsion to cause a precipitation of the wax.

11. The process of treating maize or corn oil, which comprises the heating of said oil, with steam or water, to a temperature sufficiently high to produce an emulsion and to cause part of the non-emulsified oil to separate by gravity, upon cooling, from the emulsified oil and water, separating the non-emulsified oil from the emulsified oil and water, reheating with water the emulsion so obtained, to a temperature sufficiently high to permit the balance of the non-emulsified oil to be separated, while hot, with a centrifuge, passing such emulsion through a centrifuge with a substantially equal volume of hot water to cause such separation, adding an electrolyte that will break down the colloidal state of the emulsion last obtained, heating said emulsion to a temperature sufficiently high to cause a separation of wax, and subsequently chilling said emulsion to cause a precipitation of the wax.
12. The process of treating maize or corn oil, which comprises the heating of said oil with water to a temperature of substantially 50 degrees centigrade so as to produce an emulsion and to cause part of the non-emulsified oil to separate by gravity, upon cooling, from the emulsified oil and water, separating the non-emulsified oil from the emulsified oil and water, reheating with water the emulsion so obtained to a temperature of substantially 50 degrees centigrade to permit the balance of the non-emulsified oil to be separated, while hot, with a centrifuge, passing such emulsion, while hot, through a centrifuge with a substantially equal volume of hot water to cause such separation, and adding substantially five per cent. of sodium chlorid to the emulsion last obtained, heating said emulsion to a temperature of substantially 100 degrees centigrade to cause a separation of wax, and subsequently chilling said emulsion to cause a precipitation of the wax and to cause a separation of the remaining oil from the brine.

Signed at Chicago this 18th day of September, 1917.

CARLETON JOSEPH BARTON.
